Darin M. Klemchuk(57) **CLAIM**

An ornamental design for an circuit board with LEDS for an integrated ozone laundry system, as shown and described.

DESCRIPTION

FIG. 1 is a front perspective view of an integrated energy management system according to the present disclosure;
 FIG. 2 is a front elevation view of the integrated energy management system shown in FIG. 1;
 FIG. 3 is a bottom perspective view of the integrated energy management system shown in FIG. 1; and,
 FIG. 4 is a bottom elevation view of the integrated energy management system shown in FIG. 1.
 The broken lines shown on FIGS. 1-4 illustrate unclaimed details only and form no part of the claimed design.

1 Claim, 4 Drawing Sheets
